UNITED STATES PATENT OFFICE.

EDWARD McLAUGHLIN, OF PHILADELPHIA, PENNSYLVANIA.

TROUSERS-STRETCHER.

SPECIFICATION forming part of Letters Patent No. 379,118, dated March 6, 1888.

Application filed November 26, 1886. Serial No. 219,923. (No model.)

To all whom it may concern:

Be it known that I, EDWARD McLAUGHLIN, a citizen of the United States, and a resident of Philadelphia, Pennsylvania, have invented 5 certain Improvements in Trouser Leg Stretchers, of which the following is a specification.

The object of my invention is to provide a cheap and simple form of stretcher for application to the legs of trousers, to cause the latter 10 to retain their proper shape when they are not being worn; and this object I attain in the manner which I will now proceed to describe, reference being had to the accompanying drawings, in which—

15 Figure 1 is a perspective view of a trousers-leg stretcher constructed in accordance with my invention; Fig. 2, a view of a pair of trousers, showing my improved stretcher applied to one of the legs of the same; and Fig. 20 3, a side view of a special form of stretcher embodying my invention.

25 My improved stretcher consists of a piece of wire bent so as to form a skeleton frame, comprising the opposite side bars, *a a*, a central inwardly-projecting and tapering tongue, *b*, at one end, and an outwardly-projecting tongue, *d*, at the opposite end, both of said tongues being preferably provided at the tips with coils 30 *f*, as shown; so as to enhance their lateral elasticity.

35 To the tapering tongue *b* is adapted a link, *g*, by the adjustment of which on said tongue the expansion of the inner portion of the stretcher may be regulated, for a purpose hereinafter set forth. The stretcher is of such length that it will extend from the bottom of the leg of a pair of trousers to a point above the knee of the same, and in applying the stretcher the latter is thrust into the leg from 40 the top until the coils *f* at the outer end of the tongue *d* project beyond the bottom of the leg. The leg will consequently be stretched crosswise, so as to prevent bagginess or loss of shape; but it is advisable that the fabric shall not be subjected to the pressure of the 45 stretcher at and near the knee, otherwise there is likely to be an objectionable creasing of the material at that point. After the stretcher is applied to the leg, therefore, I lightly press 50 together the opposite bars of the same at the

knee while the trousers are in the inverted position shown in Fig. 2, so that the link *g* will slip down on the tapering tongue *b* of the stretcher and will retain the knee portion of the same in this contracted condition, whereby, 55 although the stretcher fills the leg sufficiently to prevent bagging, it does not exert such outward pressure upon the fabric at and near the knee as would tend to crease the same. That end of the stretcher which is provided with 60 the inwardly-projecting tongue *b*, I term the "inner end" of the stretcher, as it occupies the position within the leg when applied thereto.

The coils *f* on the tongue *d* of the stretcher form an eye, which may be utilized as a means 65 of hanging the trousers upon a hook or nail in a wardrobe or closet.

In the special form of stretcher shown in Fig. 3 a reverse bend, *i*, is formed between the side bars, *a a*, of the stretcher and the end 70 tongue, *d*, this construction being adopted when increased elasticity of the outer portion of the stretcher is required. Both of the tongues *b* and *d* are in the same plane as the side bars, *a*, of the stretcher, so as to permit the fabric 75 to be drawn flat from one side bar to the other.

I claim as my invention—

1. A trousers-leg stretcher consisting of a skeleton frame free to expand and contract laterally, and comprising opposite side bars, 80 and a longitudinally-projecting elastic tongue interposed between the inner ends of said side bars, said tongue being in the same plane as the bars and tending to expand the latter, and the whole being formed of a continuous piece 85 of wire, all substantially as specified.

2. A trousers-leg stretcher consisting of a skeleton frame free to expand and contract laterally, and comprising opposite side bars with longitudinally-projecting elastic tongues 90 connecting said side bars at each end of the frame, said tongues being in the same plane as the side bars and tending to expand the latter, and the whole being formed of a continuous piece of wire, all substantially as specified. 95

3. A trousers-leg stretcher consisting of a skeleton frame of wire having at the ends elastic tongues with coils at the tips, all substantially as specified.

4. A trousers-leg stretcher consisting of a 100

skeleton frame of wire having at the inner end a tapering elastic tongue tending to expand the side bars of the frame, in combination with a link adapted to said tongue and serving, by adjustment longitudinally thereon, to retain the inner portion of the frame in a contracted condition, all substantially as specified.

In testimony whereof I have signed my name to this specification in the presence of two subscribing witnesses.

EDWARD McLAUGHLIN.
